UNITED STATES PATENT OFFICE.

ALFRED F. C. LOTZ, OF CHICAGO, ILLINOIS, ASSIGNOR TO ELECTRICAL ENGINEERS EQUIPMENT COMPANY, OF CHICAGO, ILLINOIS, A CORPORATION OF ILLINOIS.

RHEOSTAT.

Application filed October 15, 1925. Serial No. 62,522.

My invention relates to rheostats and has especial reference to a rheostat having particular utility in radio work.

The present invention may be characterized as an improvement upon the device disclosed in my Patent No. 1,625,479, Apr. 19, 1927, and its objects are the provision of a generally improved and simplified construction that may be economically produced and conveniently operated, and which will give a smooth, quiet, stepless, fine and accurate adjustment without any undesirable action or characteristics.

According to my present invention I provide for minimizing the inherent resistance, that is, the minimum resistance of the device.

I also provide for minimizing the stresses upon the resistance conductor of the device and upon the connection or joint between that conductor and the operating element or elements, as the case may be.

I also provide for improving the joint or connection between the insulating drum contact and the drum, and an improved contact between the drum contact and its co-operating contact.

I also provide for relieving the case or housing of any movement limiting or stopping function for the rider or circuit opening or controlling means and for relieving the housing and driving shaft of any stresses accompanying such a function.

I also provide a symmetrical contact arm or spring and end wall structure which may be assembled without predetermining its position and an improved mounting for holding the contact arms or springs firmly in position.

I also provide an improved journal for the driving shaft in the end wall of the case, an improved floating mounting of the driving gear, and an improved driving connection between said gear and the driving shaft.

I also provide an improved seating of the case or cover in its end walls and an improved arrangement and anchoring of the resistance conductor tensioning spring.

Now, in order to acquaint those skilled in the art with the construction and operation of a device embodying my present invention, I shall describe in connection with the ac-

companying drawings a particular embodiment of the invention.

55

In the drawings:

Figure 1 is a side elevational view with the case or frame in section;

60

Fig. 2 is a section taken substantially on the line 2—2 of Fig. 1;

Fig. 3 is a section taken on substantially the plane of the line 3—3 of Fig. 2;

Fig. 4 is a section taken on substantially the plane of the line 4—4 of Fig. 3;

65

Fig. 5 is a section taken on substantially the plane of the line 5—5 of Fig. 3;

Fig. 6 is an elevational view of the back end of the device;

70

Fig. 7 is a section taken on substantially the plane of the line 7—7 of Fig. 3;

Fig. 8 is a section taken on substantially the plane of the line 8—8 of Fig. 3;

Fig. 9 is a section taken on substantially the plane of the line 9—9 of Fig. 3;

75

Fig. 10 is a more or less diagrammatic view showing the improved resistance conductor terminal for minimizing the inherent or minimum resistance of the device;

Fig. 11 is a cross section through the resistance conductor taken on the line 11—11 of Fig. 10;

80

Fig. 12 is a cross section through the terminal portion of the resistance conductor taken on the line 12—12 of Fig. 10;

Fig. 13 is a detail section taken on the line 13—13 of Fig. 3;

Fig. 14 is an isometric view of the driving shaft journal which is mounted in the front end;

85

Fig. 15 is a fragmentary isometric view of the driving shaft showing the means for connecting the driving gear for rotation therewith; and

90

Fig. 16 is an isometric view of the driving gear which is mounted upon the driving shaft.

95

Merely as illustrative of the relative dimensions of a commercially practical embodiment of the device which I at present construct, the device shown in the accompanying drawings is substantially twice the size of that device. This is merely illustrative and is in no wise intended to limit the size or proportions of the invention.

100

Referring to the drawings, the device is enclosed within an oblong case having the

105

end walls or front wall 5 and back 6, which may be of suitable insulating material. The back 6 is shown in the form of a detachable cover. The walls 5 and 6 may be oblong with their ends rounded or semi-circular, each end 5 and 6 having a marginal flange 7 and in the inside or opposing surfaces of the end walls 5 and 6 are marginal grooves 8 about the flanges 7.

A cover or case 10, which may comprise a relatively thin sheet or strip of transparent material, for example, celluloid or isinglass material such as "Pyralin" is folded to conform or fit within the flange 7 with its opposite or free ends meeting or overlapping. The opposite edges of the cover 10 fit within the flanges 7 and seat in the grooves 8 so that the cover is held firmly and properly in place by the means which holds the end walls 5 and 6 together.

Rotatably mounted within the cover 10 and between the end walls 5 and 6 with their axes substantially parallel is an insulating cylinder or drum 12 and a conducting or short circuiting cylinder 13.

The cylinder 12 may be formed of insulating material such as a phenol condensation compound and it comprises an axially bored hub 14 and a surrounding cylindrical wall 15 having an open end 16 and a closed end 17. Integral webs 18 may be provided between the hub 14 and the wall 15. The cylinder 12 is rotatably journaled upon a shaft 19, the opposite ends of which are reduced to provide shoulders which abut and space the end walls 5 and 6. The reduced ends of the shaft 19 are threaded and these threaded ends extend through openings in the end walls 5 and 6 and engage in nuts 20, which when tightened or brought up clamp the end walls 5 and 6 firmly together. Suitable washers may be interposed between the end walls 5 and 6 and the nuts 20, as shown. The cylinder 12 is thus mounted to rotate on the shaft 19 and the shaft 19 is rigidly secured in the case and spaces and joins the end walls thereof.

The cylinder 13 may be of metal or suitable conducting material, such as brass or copper, and it comprises an axially bored hub 24 and a surrounding cylindrical or annular wall 25 having an open end 26 and a closed end 27. The wall 25 is provided internally with the longitudinally extending integral lug or shoulder 28 and the hub 24 terminates short of the open end of the cylinder 13. The cylinder 13 is rotatably journaled upon a shaft 29, the opposite ends of which are reduced to form shoulders which abut and space the end walls 5 and 6 symmetrically upon the opposite side of the driving shaft 30. As with the shaft 19, the reduced ends of the shaft 29 are threaded and these threaded ends extend through openings in the end walls 5 and 6 and engage

in nuts 32 which clamp the end walls 5 and 6 firmly together. As before, suitable washers are preferably interposed between the ends 5 and 6 and the nuts 32. The cylinder 13 is thus mounted to rotate on the shaft 29 and the shaft 29 is rigidly secured in the case, and with the shaft 19 provides a symmetrical spacing and joining of the ends 5 and 6.

The closed end 17 of the cylinder or drum 12 has an annular recess 35 in which is secured an annular contact or commutator ring 36. The outer end of the conducting or short circuiting drum 13 forms a contact surface for the drum 13.

The rheostat or resistance element comprises a strand of fine, relatively high resistance wire 37, such as an alloy, nichrome, or the like. One end of this wire or conductor 37 is wrapped on the drum 12 with its adjacent end turned in through a slot or recess 38, and wrapped on the projecting end of the contact ring 36. That portion of the wire 37 which is wrapped upon the contact ring 36 is soldered or otherwise connected electrically and mechanically to the ring 36 at 39.

The opposite end of the conductor 37 is wrapped upon the cylinder 13 with its end turned in through a radial opening 40 and knotted at 42 to anchor it to the cylinder 13. The external surface or periphery of the insulating cylinder 12 is threaded or grooved spirally at 43 to accommodate the turns of the wire 37, and to space and insulate them from each other. The external surface or periphery of the conducting cylinder 13 is threaded or grooved spirally at 44 in the same direction to accurately arrange the turns of the wire 37 thereon, and to guide the wire properly to and from the cylinder 12.

At one end of the wire 37 preferably has a dead turn or two on the drum 12, that is, a turn or two which remains on the drum in the complete upwrapped position of the drum, and at its opposite end the wire 37 preferably has a similar dead turn or two on the drum 13. This provides belt friction between the respective drums and the opposite ends of the conductor 37 and relieves the joints or connections of the terminals of the wire 37 with the ring 36 and drum 13, respectively, of any stresses at the limits of rotation of the drums.

The opposite ends of the wire 37 have terminals or circuit connections for connecting the device serially or otherwise in the desired circuit. These comprise spring contact or brush arms 48 and 50. One of these arms is secured to the end wall 6 by a screw 52 which extends through and engages in a nut 53 which, with an additional nut 54, provides a binding post to which the desired circuit conductor may be conveniently connected mechanically and electrically. The

mounting of the other contact arm upon the end wall 6 and its circuit connection are substantially the same. Spring washers 55 are preferably interposed between the end 6 5 and the nuts 53 to keep the contact arms tightly clamped to the back or cover 6.

The contacting ends of the arms 48 and 50, which have wiping contact on the ring 36 and drum 13, respectively, are preferably 10 split or divided longitudinally at 58 to form spring ends for good, firm and maximum contact with the ring 36 and drum 13 at all times.

The contact arms 48 and 50 are mounted 15 with their lengths extending longitudinally of the back 6 and preferably with one disposed on each side of the driving shaft 30. This provides a compact and symmetrical arrangement. The arms 48 and 50 are carried by the back 6 and removed and assembled therewith, the symmetrical disposition of the arms thereon making a predetermined positioning of the back in assembling unnecessary because which ever 20 way the back is applied one arm will engage the ring 36 and the other arm will engage the drum 13. Either arm will co-operate with either drum and when one arm is in co-operation with one drum, the other arm 25 co-operates with the other drum.

For the purpose of holding the arms firmly in place and preventing accidental turning on their posts or screws 52, the back or end 6 preferably has a pair of integral 30 projecting lugs or shoulders 60 co-operating with the anchored ends of the arms 48 and 50, as shown in Fig. 6.

For the purpose of firmly securing the ring 36 in the recess 35, I tin the washer or ring 36, or coat it with a suitable relatively soft conducting coating. The washer may be of brass, for example, and it may be pressed into the recess in the end of the drum 12. This tinning or coating provides firm adhesion of the washer to the insulating drum 12, and it provides a soft contact surface, which upon operation of the device I find is quickly grooved by the contact arms 48 or 50, this grooving of the arm thereinto 45 forming a good, maximum contact at all times. Subsequent hand tinning for connection of the wire 37 to the ring is also hereby avoided. The contact end of the drum 13 may be similarly tinned or coated.

The driving shaft 30 extends between the cylinders or drums 12 and 13 which makes for compactness and symmetry. The inner or back end of the shaft 30 is reduced at 65 and this reduced end is rotatably journaled in the back cover wall 6. The forward part of the shaft 30 is enlarged at 66 and the enlarged shaft part 66 is rotatably journaled in a bearing bushing or sleeve 68. The bushing 68 comprises an externally threaded 60 cylindrical sleeve or thimble having an en-

larged non-circular head 70 of square or other polygonal formation, for example, which may be formed integral with the bushing sleeve. The inside surface of the wall 5 has a non-circular recess 72 conforming to the head 70 and adapted to receive or accommodate same, the engagement of the head 70 in this recess 72 holding the bushing rigidly against turning in the wall 5 and limiting its forward or outward movement therethrough. A nut 73 threaded externally upon the bushing 68 up into engagement with the wall 5, binds the bushing rigidly in said wall.

The outer end of the shaft 30 may be of 80 sufficient length to pass through an insulating panel or plate 75 or other support, and may be clamped therein by lock nuts 76. The outer end of the shaft has an operating knob 78 for turning the shaft. This knob 85 78 may be of insulating material with a grooved or knurled periphery and a metal insert or sleeve 79 secured axially in the hub portion of the knob. The insert 79 is threaded to accommodate a radial screw 81 90 which threads through the sleeve 79 and into engagement with the shaft 30 to secure the knob rigidly thereon.

Between the front cover or end wall 5 and the forward end of the cylinders or 95 drums 12, 13, the driving shaft 30 has secured thereto a driving gear or pinion 82. The pinion 82 has a non-circular recess 83, as shown in Fig. 16, which may be square, and integral with the driving shaft 30 is 100 a non-circular portion 84 of a contour corresponding to the recess 83. In assembling the gear 82 is slipped upon the shaft 30 with the non-circular portion 84 of the shaft fitting in the recess 83 and fixing the gear on 105 the shaft for rotation therewith. Connecting pins or keys between the gear and shaft, which are undesirable because of the relatively small dimensions of the parts, are thus avoided and, at the same time, a floating 110 mounting of the gear 82 between the end wall 5 and drums 12, 13 is secured, the gear being also conveniently removable from the shaft.

The driving gear 82 is disposed between 115 and meshes with a pair of gears 86 and 87, one for each of the cylinders or drums 12 and 13, the particular gear ratio shown being substantially two to one, the drums performing one revolution for each two revolutions of the gear 82 or main shaft 30. The gear 86 may be formed by cutting the teeth directly in the end of the cylindrical insulating wall 15 of the drum 12, which makes a rigid integral unit in which attachment 120 means or connections between the gear and drums are eliminated.

The gear 87 has an axially bored hub 125 loosely rotatable on the shaft 29, and projecting from the inner surface of the gear 130

87 is a driving lug 89 which may be formed integral with the gear 87. Disposed within the cylinder 13 and coiled about the hub 24 is a helical tension spring 90. One end of 5 this spring is turned out at 91 into engagement with the lug 28. The opposite end is turned out at 92 for engagement or co-operation with the lug 89, providing a yieldable or take-up connection between the drum 13 10 and the gear 82, for maintaining the resistance wire 37 always properly tensioned or tightened.

In winding the resistance conductor in the assembly of the device, the lugs 28 and 92 15 may be first placed in engagement so that the gear 87 and drum 13 are driven positively together. Upon completing the winding the lug 92 may be sprung past the lug 28 in the direction of tensioning of the 20 spring 90 (Figure 8), so that thereafter in the operation of the device the gear 87 turns the drum 13 through the spring 90. The spring 90 is shown tensioned in Figure 8 by the relative movement which accompanied 25 separation of the lugs 28 and 92 in a clockwise direction in Figure 8. The resistance conductor 37 is thereby maintained taut and properly tensioned at all times.

For the purpose of opening the controlling 30 circuit when the resistance is entirely in circuit and for closing it when operation is desired and it is desired to reduce the resistance, an abutment block or rider 95 is provided. This block or rider 95 may be of 35 insulating material having a metal insert 96 threaded upon the threaded portion of the shaft 30. The rider 95 has depressions in its opposite sides conforming generally to the peripheries of the drums 12 and 13 40 between which it fits and is held against turning and guided between the drums. The opposite ends of the rider 95 extend radially from the shaft between the drums for engagement with the contact arms 48, 45 50, as the rider reaches the limit of its movement toward the block 6. When the driving shaft has been turned to place the drums with substantially the entire resistance effective, the rider 95 will have shifted along 50 the shaft 30 to bring its arms 98 against the contact arms 48, 50, and to lift or disengage said arms 48, 50 from contact with the ring 36 and drum 13, opening the controlled circuit. When the knob 78 is turned 55 in the opposite direction, the first movement or rotation of the shaft causes withdrawal of the rider 95 from the contact arms 48, 50 and said arms spring into electrical engagement with the ring 36 and drum 13.

60 For the purpose of limiting the movement of the rider toward the end wall 6, I provide stop means on the shaft 30 itself. This stop means may be in the form of a diametrical pin 100 secured in the shaft and 65 projecting radially at opposite ends there-

from. The provision of a stop on the shaft relieves the case of any rider stopping purpose and thereby of any stresses or pressures which might accompany such a purpose. It also relieves the driving shaft 30 and threads 70 thereon of any stresses incidental to the stopping or limiting of the movement of the rider.

From the foregoing it will now be apparent that the resistance conductor 37 is 75 adapted to be transferred from one drum to the other by turning or rotating the drums. When substantially all of the conductor 37 is on the drum 12, substantially the entire resistance is in circuit, whereas 80 when the conducting drum 13 is in its completely wound condition with the drum 12 unwound, the minimum resistance is in circuit. With the insulating drum wound and the device operated to transfer the resistance 85 conductor to the contact drum, the conductor is short circuited as it passes on to the conducting drum, and this decreases the resistance in the circuit.

For the purpose of minimizing the inherent 90 or minimum resistance of the device, I provide for decreasing the resistance of that portion of the terminal of the wire 37, which connects the contact on the drum 12 with the drum 13 when the drum 12 is unwound. 95

This may be done by laying a length of wire 105 (Figs. 10 and 12) or any other suitable conducting strip of relatively great conductivity, such as copper, along the insulating drum terminal of the high resistance wire 37 and sweating, soldering, or otherwise securing it along and in parallel with the terminal of the wire 37. Thus, when the drum 12 is unwound and substantially the entire resistance is short-circuited 100 by the drum or cylinder 13, the contact 36 and cylinder 13 are connected by a terminal of high conductivity, so that the resistance is less than the inherent resistance of a length of the wire 37 sufficient to connect 110 the drums.

I do not intend to be limited to the precise details shown and described.

I claim:

1. In a resistance device, the combination 115 of a drum, a contact on said drum, a resistance conductor connected to said contact and adapted for winding upon and unwinding from the drum, and means of relatively high conductivity along the effective terminal portion of said resistance conductor for decreasing the resistance of said terminal portion beyond the normal resistance of said conductor. 120

2. In a resistance device, the combination 125 of an insulating drum, a short circuiting drum, a resistance conductor on said drums, means for shifting the conductor from one of said drums to the other, and means of relatively high conductivity along 130

- the effective insulating drum terminal of said resistance conductor for decreasing the inherent resistance of said conductor when same is in maximum short circuit position.
- 5 3. In a resistance device, the combination of an insulating drum, a short circuiting drum, a resistance conductor on said drums, means for shifting the conductor from one of said drums to the other, a contact on the insulating drum, and a terminal of relatively high conductivity for said resistance conductor, said terminal connecting the short circuiting drum and the insulating drum contact when the resistance conductor 10 is substantially entirely upon the short circuiting drum.
4. In a device of the class described, the combination of an insulating cylinder, a short-circuiting cylinder, resistance means 15 carried by said cylinders, separable contacts for said resistance means, a shaft for turn-
ing the cylinders to transfer said resistance means from one to the other, means operable along said shaft for separating said contact means and means on the shaft for limiting 20 the movement of said last means.
5. In combination, a housing including end walls, a rheostat within the housing and including rotatable drums, shafts rotatably supporting the drums and having reduced terminals passing through said walls, the walls being spaced apart by the shafts and having grooves in their inner faces, a member forming a closure wall extending between the end walls with its edges seating 25 in said grooves, and means cooperating with the terminal elements of the shafts and the body portions of said shafts for securing the end walls against relative movement.
- 30 In witness whereof, I hereunto subscribe 35 my name this 13 day of October, 1925.

ALFRED F. C. LOTZ.
